(57) **CLAIM**

The ornamental design for a two part hinge housing, as shown and described.

DESCRIPTION

FIG. 1 is an isometric view of a first embodiment of an ornamental design for a two part hinge housing showing my new design with the hinge open;
FIG. 2 is a top view thereof;
FIG. 3 is a bottom view thereof;
FIG. 4 is a front view thereof;
FIG. 5 is a rear view thereof;
FIG. 6 is a right side view thereof;
FIG. 7 is a left side view thereof;
FIG. 8 is an isometric view of the two part hinge housing of FIGS. 1-7 with the hinge closed;
FIG. 9 is a top view thereof;
FIG. 10 is a bottom view thereof;
FIG. 11 is a front view thereof;
FIG. 12 is a rear view thereof;
FIG. 13 is a right side view thereof;
FIG. 14 is a left side view thereof;
FIG. 15 is an isometric view of a second embodiment of an ornamental design for a two part hinge housing showing my new design with the hinge open;
FIG. 16 is a top view thereof;
FIG. 17 is a bottom view thereof;
FIG. 18 is a front view thereof;
FIG. 19 is a rear view thereof;
FIG. 20 is a right side view thereof;
FIG. 21 is a left side view thereof;
FIG. 22 is an isometric view of the two part hinge housing of FIGS. 15-21 with the hinge closed;
FIG. 23 is a top view thereof;
FIG. 24 is a bottom view thereof;
FIG. 25 is a front view thereof;
FIG. 26 is a rear view thereof;
FIG. 27 is a right side view thereof; and,
FIG. 28 is a left side view thereof.
The dashed lines shown in FIGS. 1-28 illustrate portions of the two part hinge housing which form no part of the claimed design.
